US00D984188S

(12) **United States Design Patent** (10) **Patent No.:** **US D984,188 S**
Melkonian (45) **Date of Patent:** **** Apr. 25, 2023**

(54) **DISPENSER**

(71) Applicant: **Brio Water Technology, Inc.**, City of Industry, CA (US)

(72) Inventor: **Arman Melkonian**, Granada Hills, CA (US)

(**) Term: **15 Years**

(21) Appl. No.: **29/776,544**

(22) Filed: **Mar. 31, 2021**

(51) LOC (14) Cl. **20-01**

(52) U.S. Cl.

USPC **D7/307**; D7/311; D7/313; D7/315

(58) **Field of Classification Search**

Primary Examiner — Joseph Kukella

Assistant Examiner — Arva P Adams

(57) **CLAIM**

The ornamental design for a dispenser, as shown and described.

DESCRIPTION

FIG. 1 is a top perspective view, showing my new design; FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right-side view thereof;

FIG. 7 is a top plan view thereof; and,

FIG. 8 is a bottom plan view thereof.

The broken lines show portions of the dispenser that form no part of the claimed design.

1 Claim, 8 Drawing Sheets
